FIG. 1 is a front perspective view of a pallet according to a first embodiment of our new design;

FIG. 2 is a cross-sectional perspective view taken along line 2-2 of FIG. 4;

FIG. 3 is a right side elevational view thereof, the left side elevational view being identical thereto;

FIG. 4 is a front elevational view thereof, the rear elevational view being identical thereto;

FIG. 5 is a top plan view thereof;

FIG. 6 is a bottom plan view thereof;

FIG. 7 is a cross-sectional view thereof taken along line 7-7 of FIG. 1;

FIG. 8 is a cross-sectional plan view thereof taken along line 8-8 of FIG. 3;

FIG. 9 is a cross-sectional plan view thereof taken along line 9-9 of FIG. 3; and,

FIG. 10 is a bottom perspective view thereof.

The evenly-spaced broken lines shown in the drawings are for the purpose of illustrating environmental structure and form no part of the claimed design. The dash-dot lines are included to show boundaries that form no part of the claimed design.
